CLAIM

The ornamental design for a watch strap as shown and described.

DESCRIPTION

1.1 : Perspective

1.2 : Right

1.3 : Left

1.4 : Front

1.5 : Back

1.6 : Top

1.7 : Bottom

1.8 : Top

1.9 : Back

1.10 : Bottom

1.11 : Top

1.12 : Right

1.13 : Left

1.14 : Perspective

The design is that of a watch strap; the essential characteristics of the design are featured in its shape; Reproductions **1.1** to **1.7** are views in folded position; reproductions **1.8** to **1.14** are views in unfolded position; The broken lines in the drawings showing a watch represent environmental subject matter only that forms no part of the claimed design.
